UNITED STATES PATENT OFFICE

158,596

PLANT WATERING DEVICE

Jon Keating Lack, Beverly Hills, Calif.

Application October 23, 1948, Serial No. 149,263

Term of patent 3½ years

(Cl. D35—2)

To all whom it may concern:

Be it known that I, Jon Keating Lack, a citizen of the United States of America, residing at 128 South Camden Drive, Beverly Hills, county of Los Angeles, State of California, have invented a new, original, and ornamental Design for a Plant Watering Device, of which the following is a specification, reference being had to the accompanying drawing, forming a part thereof.

Figure 1 is a perspective view of a plant watering device illustrating my new design;

Figure 2 is a side elevational view of the device of Figure 1; and

Figure 3 is a top plan view thereof.

I claim:

The ornamental design for a plant watering device, as shown.

JON KEATING LACK.
